DESIGN FOR A TABLE ORNAMENT OR SIMILAR ARTICLE

Robert A. Baur, Philadelphia, Pa.

Application July 30, 1935, Serial No. 57,865

Term of patent 7 years

To all whom it may concern:

Be it known that I, Robert A. Baur, a citizen of the United States, residing at Philadelphia, in the county of Philadelphia and State of Pennsylvania, have invented a new, original, and ornamental Design for a Table Ornament or Similar Article, of which the following is a specification, reference being had to the accompanying drawing, forming part thereof.

Fig. 1 is a side elevational view of the article showing my design,

Fig. 2 is a top plan view thereof.

Fig. 3 is a sectional view of the finial taken at 3—3 of Fig. 1, and

Fig. 4 is a sectional view taken at 4—4 of Fig. 2 illustrating a typical form of the bell-shaped elements.

I claim:

The ornamental design for a table ornament or similar article substantially as shown.

ROBERT A. BAUR.
